UNITED STATES PATENT OFFICE.

GEORGE E. McMASTER, OF BELLINGHAM, WASHINGTON.

MOVING-SIGN DEVICE.

1,365,520.

Specification of Letters Patent. Patented Jan. 11, 1921.

Application filed September 15, 1920. Serial No. 410,383.

To all whom it may concern:

Be it known that I, GEORGE E. McMASTER, a citizen of the United States, and resident of Bellingham, in the county of 5 Whatcom and State of Washington, have invented a new and useful Moving-Sign Device, of which the following is a specification.

My invention relates to improvements in 10 moving sign devices of the sort which have both stationary and moving signs, the latter appearing and pausing while covering some of the stationary signs, and then disappearing and pausing while covered by other stationary signs.

I have applied for a patent for an improved moving sign device which was filed 15 August 17, 1920, Serial No. 404,057 suitable for general purposes. I have also applied 20 for a patent for an improvement of similar devices more especially of a decorative character, filed September 1, 1920, Serial No. 407,458. The object of this invention is to provide a structure and mechanism 25 especially adapted for operating moving signs of large dimensions, even under difficult outside conditions caused by storms and wind pressures, and yet both simple and durable and dependable in action. I attain 30 this object with the mechanism illustrated in the accompanying drawing in which Figure 1 is a front elevation of my device, Fig. 2 is a bottom plan view of Fig. 1 and Fig. 3 is an end elevation of each of three 35 segmental bevel gears.

Similar characters refer to similar parts throughout. Certain parts are broken away for lack of space for the illustration, or to show other parts hidden thereby.

40 More particularly: 4 is the base or back of the device to which the operative and protective parts are fastened. It is shown as of solid construction, but in practice I prefer to make it of angle bar construction 45 with openings through which the interior is accessible.

5 is the cover and comprises a flat part with box-like sides fastened to back 4. 5^a, 5^b and 5^c are three rectangular openings in 50 the upper part of said cover in horizontal line. The part of cover 5 below said openings is used to mount one or more stationary signs, as shown at 100.

6 is a plane metal sheet fastened to and 55 within cover 5 near and parallel with the same and extending from the top downward

to end below the openings 5^a, 5^b and 5^c, and on it are mounted stationary signs 6^a, 6^b and 6^c respectively registering with said openings.

7, 8 and 9 are three sign carriers each 60 adapted for mounting signs and each having fastened on its lower edge one of lugs 7^a, 7^b and 7^c respectively. 7^b, 7^b; 8^b, 8^b and 9^b, 9^b, respectively, are three pairs of tracks 65 fastened to the inner side of cover 5, each pair to mount the wheels 7^c, 8^c and 9^c, respectively, of sign carriers 7, 8 and 9.

10, 11 and 12 are three levers each having 70 a slot, 10^a, 11^a and 12^a, respectively, near its shorter end, and each fulcrumed on one of posts 13, 14 and 15 at 10^b, 11^b and 12^b respectively. 10^c, 11^c and 12^c are three links 75 each connecting the longer end of one of levers 10, 11 and 12 to one of studs 7^a, 8^a and 9^a respectively, 10^d, 11^d and 12^d are counterweights each fastened to the shorter end of one of levers 10, 11 and 12 respectively.

Said posts 13, 14 and 15 are fastened to 80 base 4.

16, 17 and 18 are three disks, each 85 mounted for revolution on a stud in the outer end of one of posts 28, 29 and 30 respectively.

19, 20 and 21 are three crank pins, one in each of said disks, and one engaged in each of slots 10^a, 11^a and 12^a respectively.

22, 23 and 24 are three spring pawls, each fastened to a bracket on one of posts 28, 90 29 and 30, and having a V-form bit engaging in one of two V-form notches 25, 26 and 27 on the opposite ends of a diameter in the periphery of each of disks 16, 17 and 18 respectively. Only one of said two notches 95 is shown in each disk, except in disk 16.

28, 29 and 30 are three posts fastened to 100 base 4 and mounting disks 16, 17 and 18 and pawls 22, 23 and 24, respectively, as stated.

31, 32 and 33 are three segmental bevel 100 gears, each engageable with one of bevel gears 34, 35 and 36 respectively. Said gears 34, 35 and 36 are each fastened to one of disks 16, 17 and 18 respectively.

87 is a shaft mounted for revolution in 105 bearings in posts 14, 15, 28, 29 and 30, and it mounts fixed for revolution therewith segmental gears 31, 32 and 33, and also mounts on its right-hand end fixed bevel gear 38 meshed with bevel gear 39^a.

110 39 is a worm wheel mounted for revolution on a stud fastened in boss 39^b, which

is fastened to base 4. Said worm wheel has fastened thereto bevel spur wheel 39^a meshed with 38.

40 is an electric motor on bracket 40^c, 5 which is fastened to base 4. Said motor is electrically connected to a source of electricity, neither said connections nor said source of power are shown.

41 is the shaft of said motor the outer end 10 of which finds a bearing in a bracket on post 30 and mounts, fixed for revolution therewith, worm 42 in engagement with said worm wheel.

In operation: Motor 40, acting through 15 reducing gears 42, 39, 39^a and 38 causes the continuous but slow revolution of shaft 37 and segmental gears 31, 32 and 33. There are only sufficient teeth on each of segmental gears 31, 32 and 33 to cause half a revolution 20 in each of crank disks 16, 17 and 18 respectively. Said segmental gears are fixed on shaft 37 relatively as shown in Fig. 3. The teeth on each of said segmental gears occupy but three fifteenths of its circumference. Then the three acting in order 25 revolve said disks in order with a pause between each semi-revolution of two thirds the time of said semi-revolution. The joint action then is to cause the movement of but 30 one disk at a time while the other disks are at rest and also a period of rest between each disk movement. Also the disk movements are slow. Each semi-revolution of a disk causes one of said sign carriers to 35 move from one extreme position to the other, by the operation of the mechanism shown. The counterbalances on the shorter ends of levers 10, 11 and 12 compensate for the weight of the sign carriers on the longer 40 ends of said levers, and the force required to move said sign carriers either up or down is substantially equal.

The extreme positions of said carriers are indicated either in full or dotted lines in 45 Fig. 1. The illustrated position of the movable parts assumes that the action of motor 40 has caused segmental gear 31 to turn disk 16 through a semi-revolution, moving sign carrier 7 from its dotted position at 7', behind the lower part of cover 5, to its full-line position at 7, where it is exposed and 50 also covers fixed sign 6^a. The absence of teeth on any of said segmental gears for 48° then allows each of the disks to remain 55 stationary, which condition is made doubly sure by the engagement of the V-form bits of the spring pawls in the V-form notches in the disks. As illustrated, the period of pause of said disks comes at 60 times when their crank pins have carried levers 10, 11 and 12 into positions where slots 10^a, 11^a and 12^a are each substantially at right angles to a disk radius through said pins, when pressure from said levers 65 on said pins can not operate to revolve said

disk. After the said 48° has been turned by shaft 37 segmental gear 32 is brought into engagement with gear 35 on disk 17 and said disk is turned, forcing the bit of pawl 23 out of engagement with one of notches 26 in said disk, and swinging lever 11 on its fulcrum at 11^b, through its dotted-line arcs, causing sign carrier 8 to move from its full-line position to its dotted-line position at 8' in Fig. 1, moving it from 70 a covered position behind cover 5 to an exposed position above where it covers fixed sign 6^b. Then there is a pause in all sign movements, while shaft 37 turns through another arc of 48°, when segmental gear 80 33 engages with gear 36 causing disk 18 to turn through a semi-revolution and, through the operation of crank 21^a, lever 12 turns on fulcrum 12^b, through its dotted-line arcs, moving sign carrier 9 from its 85 full-line position behind cover 5 to its dotted-line position at 9' where it is exposed and covers fixed sign 6^c. Then a period of pause occurs in the three movable signs while shaft 37 revolves through another arc 90 of 48° when segmental gear 31 engages with gear 34 and sign carrier 7 is returned to its dotted-line position behind cover 5 and stationary sign 6^a is again exposed. Thus the movements of the sign carriers continue in 95 regular order with pauses between.

The slow upward movement of the sign carriers affords opportunity to read each sign as fast as it appears, while the slow downward movement of said carriers affords opportunity to read the stationary signs, alternately covered by said sign carriers, as fast as they are exposed.

The simple and reliable character of the mechanism shown, together with the roller 105 mounting of the sign carriers, insure continuity of operation even against considerable opposition from wind pressure and the like.

One of several methods may be used to 110 fasten signs to the sign carriers and to cover 5: The edges of the sign carriers may be bent up and over to form a retaining frame for cards, cards or paper on which the signs are depicted may be pasted on said carriers 115 and on said cover, also said signs may be painted directly on the surfaces of said carriers and said cover.

Having thus fully disclosed my invention, what I claim as new and desire to secure by 120 Letters Patent is,—

1. In a moving sign device in combination, a sign carrier adapted for mounting a sign, means for mounting said carrier for forth and back movements, a fulcrumed 125 lever one end of which is connected to said carrier and the other end is connected to a crank, said crank mounted for revolution, and means to cause said crank to alternately make a one-half revolution and then pause. 130

2. In a moving sign device in combination, a sign carrier, adapted for mounting a sign, means for mounting said carrier for forth and back movements, a fulcrumed lever one end of which is connected to said carrier and the other end connected to a crank, said crank mounted for rotation, a gear fixed concentric to said crank, a segmental gear mounted for rotation and engageable with said crank gear during a one-half revolution only of said crank for one entire revolution of said segmental gear, and means to continuously revolve said segmental gear.
3. In a moving sign device in combination, a plurality of stationary signs, a plurality of sign carriers each adapted for mounting a sign and each movable forth and back to cover or expose one of said stationary signs and to be covered by another one of said stationary signs or to pass from behind a cover, means for mounting said sign carriers for forth and back movements, a plurality of fulcrumed levers each having one end connected to one of said sign carriers and its other end connected to a crank, a plurality of cranks each mounted for rotation, a plurality of gears each fixed concentric to one of said cranks, a plurality of segmental gears mounted for rotation each engageable with one of said crank gears during a one-half revolution only of said crank gear for one entire revolution of said segmental gear, and means to slowly and continuously revolve said segmental gears.
4. In a moving sign device in combination, a plurality of stationary signs, a sign carrier adapted to mount a sign movable forth and back to cover and uncover one of said stationary signs and to pass behind and from behind another of said stationary signs, a disk mounted for revolution and having a crank pin and two diametrical, peripheral notches, a fulcrumed lever connected to said sign carrier and having a slideway engaged with said crank pin, a pawl having a V-form bit engageable with each of said peripheral notches, and means to cause said disk to alternately revolve through a one-half revolution, only, and pause when said lever is substantially at right angles with a disk radius through said crank pin and when said pawl engages one of said notches.
5. In a moving sign device in combination, a plurality of stationary signs, a sign carrier adapted to mount a sign movable forth and back to cover and uncover one of said stationary signs and to pass behind and from behind another of said stationary signs, a disk mounted for revolution and having a crank pin and two diametrical, peripheral notches, a fulcrumed lever connected to said sign carrier and having a slideway engaged with said crank pin, a pawl having a V-form bit engageable with each of said notches, a gear fixed concentric to said disk, a segmental gear mounted for revolution engageable with said disk gear for only one half revolution of said disk for each entire revolution of said segmental gear, said semi-revolutions of said disk gear beginning and ending when said lever is substantially at right angles with a disk radius through said crank pin and when said pawl is engaged with one of said notches, and means to slowly and continuously revolve said segmental gear.
6. In a moving sign device in combination, a plurality of stationary signs; a plurality of sign carriers, each adapted to mount a sign and each movable forth and back to cover or expose one of said stationary signs and to pass behind and from behind another of said stationary signs; a pair of tracks for each sign carrier; a set of wheels fastened to each of said carriers operable on said tracks; a plurality of fulcrumed levers, each having one end connected to one of said sign carriers and its other end slidably connected to a crank pin; a plurality of crank disks, each having a crank pin engaged with one of a plurality of lever slideways and each also having two peripheral, diametrical notches; a plurality of spring pawls, each having a V-form bit engageable with each of said notches; a plurality of gears each fixed concentric to one of said disks, a plurality of segmental gears mounted fixed for rotation on and with a mounted revoluble shaft, and each engageable with one of said disk gears for one-half revolution only of said disk gear during each entire revolution of said segmental gear; and means to slowly and continuously revolve said segmental gear shaft.

GEORGE E. McMASTER.
